WITNESS:

H. Sherburne

UNITED STATES PATENT OFFICE.

ROBERT H. SMILIE, OF OAKLAND, CALIFORNIA.

EYE GUARD.

Application filed August 24, 1922. Serial No. 583,998.

To all whom it may concern:

Be it known that I, ROBERT H. SMILIE, a citizen of the United States, and a resident of Oakland, county of Alameda, and State of California, have invented a certain new and useful Eye Guard, of which the following is a specification.

The invention relates to devices adapted to be worn on the forehead to intercept perspiration and prevent it from running into the eyes of the wearer.

An object of the invention is to provide a device adapted to be worn on the forehead to absorb and retain perspiration and overcome the annoyance caused by the perspiration running into the eyes.

Another object of the invention is to provide a device for the purpose stated which may be used in combination with a hat, cap, helmet, vizor or other head gear.

A further object of the invention is to provide a detachable absorbent pad or strip which may be readily removed from the hat, cap, helmet or vizor for the purpose of cleansing or renewal.

The invention possesses other advantageous features, some of which, with the foregoing, will be set forth at length in the following description where I shall outline in full, that form of the invention which I have selected for illustration in the drawings accompanying and forming part of the present specification. In said drawings I have shown one form of device embodying my invention, but it is to be understood that I do not limit myself to such form, since the invention, as set forth in the claims, may be embodied in a plurality of forms. In the drawings I have shown the device incorporated in an athlete's vizor, but it is to be understood that it may be used with a vizor or with a hat, cap, helmet or other head gear. Vizors are universally worn by tennis players and other athletes to shade their eyes. In the heat of the game much perspiration is induced and this perspiration runs into the eyes, causing the player to be greatly handicapped and annoyed. By use of the device of my invention, the perspiration is intercepted and retained.

Referring to the drawings:

Figure 1 is a perspective view of an athletic vizor equipped with the device of my invention;

Fig. 2 is a cross section through the vizor positioned on the head of the wearer;

Fig. 3 is a view of the absorbent pad or strip removed from the vizor;

Fig. 4 is a detail showing the means detachably connecting the pad or strip to the vizor.

In accordance with my invention, I provide a trough shaped device adapted to fit the forehead of the wearer, with the trough opening toward the forehead, and in the trough I arrange a pad or strip of absorbent material which contacts with the forehead of the wearer, and absorbs the perspiration. The pad preferably projects beyond the edges of the trough, so that it contacts with the forehead, intercepting the perspiration and at the same time forming a soft contact with the forehead.

In the drawings I have shown the invention as applied to a vizor frequently worn by athletes, such as tennis players. The vizor 2 is preferably made of fabric, such as felt, and is provided with a stiffening lining of suitable material. The vizor is lune shaped, being curved on its inner edge 3 to fit the forehead, against which it is held by an elastic band 4, which encircles the head. The inner edge of the vizor is finished with braid or cord 5. Secured to the under side of the vizor adjacent the inner edge, by a line of stitching which is substantially concentric with the inner edge, is a band or strip 6 of fabric such as linen or muslin, which forms a trough with the vizor. The strip 6 is stitched to the vizor along the outer edge of the strip and the inner edge of the strip, which is spaced from the inner edge of the vizor, is provided with a stuffed hem 7 to provide a large soft contact area.

Disposed in the trough is an elongated absorbent pad 8, preferably composed of absorbent cotton enclosed in an envelop of cotton gauze. The pad is preferably removable and for that purpose is provided on its ends with loops 9 which engage hooks 12 attached to the underside of the vizor and lying within the trough. The pad may be readily removed for laundering or renewal and the fresh pad may readily be inserted. The pad extends across the forehead from temple to temple, so that all perspiration is intercepted and absorbed.

I claim:

1. The combination with a vizor, of a strip of material secured to the vizor and forming therewith a trough opening along the inner edge of the vizor and a pad of

absorbent material disposed in the trough and adapted to contact with the forehead.

2. The combination with a vizor, of a strip of material secured to the vizor and forming therewith a trough opening along the inner edge of the vizor and a pad of absorbent material detachably disposed in the trough and adapted to contact with the forehead.

10 3. The combination with a vizor, of a strip of material secured to the vizor and forming therewith a trough opening along the inner edge of the vizor, a pad of absorbent material disposed in the trough and 15 adapted to contact with the forehead and means adapted to pass around the back of the head to hold the vizor in place on the forehead.

4. The combination of a vizor, an absorbent pad and means to hold the absorbent pad wholly below the inner edge of the vizor.

20 5. The combination with a vizor of a pad

disposed wholly below and projecting inwardly beyond the inner edge of the vizor adapted to contact with the forehead and 25 hold the inner edge of the vizor from the forehead.

6. The combination with a vizor, of a strip of material secured to the underside of the vizor and forming therewith a trough opening along the inner edge of the vizor and a pad of absorbent material in the trough projecting inwardly beyond the inner edge of the vizor to hold the inner edge of the vizor from the forehead. 30

7. The combination with a vizor, of a pad of absorbent material and means on the vizor arranged to hold said pad on the under side of the vizor and in contact with the forehead. 40

In testimony whereof, I have hereunto set my hand.

ROBERT H. SMILIE.
